(57) **CLAIM**

We claim the ornamental design for an implement connection system, as shown and described.

DESCRIPTION

FIG. 1 is a front perspective view of an implement connection system connected to loader arms according to the present disclosure.

FIG. 2 is a rear perspective view of the implement connection system connected to loader arms shown in FIG. 1, with the implement connection system further connected to an implement.

FIG. 3 is a front perspective view of the implement connection system shown in FIG. 1.

FIG. 4 is a rear perspective view of the implement connection system shown in FIG. 1.

FIG. 5 is a right side elevation view of the implement connection system shown in FIG. 1.

FIG. 6 is a left side elevation view of the implement connection system shown in FIG. 1.

FIG. 7 is a front elevation view of the implement connection system shown in FIG. 1.

FIG. 8 is a rear elevation view of the implement connection system shown in FIG. 1.

FIG. 9 is a top plan view of the implement connection system shown in FIG. 1; and,

FIG. 10 is a bottom plan view of the implement connection system shown in FIG. 1.

The broken lines showing the loader arms in FIGS. 1 and 2, the implement in FIG. 2, the control interface in FIGS. 1-10, the cable assembly in FIGS. 1-10, the pin securement assembly in FIGS. 1-10, and the ridge pattern in FIGS. 1-10 are included for environmental purposes only and form no part of the claimed design.
